UNITED STATES PATENT OFFICE.

JOHN J. SPINKS, OF WATERTOWN, MASSACHUSETTS.

SIGN.

1,208,683.

Specification of Letters Patent. Patented Dec. 12, 1916.

Application filed November 10, 1913. Serial No. 800,147.

To all whom it may concern:

Be it known that I, JOHN J. SPINKS, a citizen of the United States, residing at Watertown, in the county of Middlesex and State of Massachusetts, have invented certain new and useful Improvements in Signs; and I do hereby declare the following to be a full, clear, and exact description of the invention, such as will enable others skilled in the art to which it appertains to make and use the same.

This invention comprehends improvements in signs and relates more particularly to those of metal and concrete construction which are especially adapted for use as street indicators, but which may also be used for other purposes.

One of the objects of the invention is to provide a sign of this nature which shall be of extremely simple construction, cheap to manufacture and which will be almost unaffected by the action of the elements.

Another and more specific object of the invention is to provide a sign including a metallic frame, wire mesh secured in said frame, a layer of plastic material secured within the frame to said wire mesh and letters having retaining loops which are embedded within the plastic material.

The invention also aims to generally improve signs of this nature to render them more useful, practical and commercially desirable.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a front elevation of my improved sign, Fig. 2 is a transverse section taken on the plane of line 2—2 of Fig. 1, and Fig. 3 is a fragmentary sectional view taken on the plane of line 3—3 of Fig. 1.

Referring in detail to the drawings by numerals, 5 designates the frame of my improved sign, said frame being preferably formed of aluminum composition and appearing concavo-convex in cross section. This frame may be of any desired shape and for the purpose of illustration I have shown

a substantially rectangular frame which presents curves that are pleasing to the eye and the concave surface 7 thereof is disposed inwardly to provide an endless groove or channel. A wire mesh 6 is secured to the inner concave face 7 of the frame centrally between the edges thereof and panels of plastic material 8 are applied to opposite sides of the mesh and are seated in the groove or channel 7, as shown in the sectional views forming panels on opposite sides of the wire mesh. This plastic material may be suitably colored and supports the letters 9 which may be applied to one or both sides of the sign as may be desired. The edges of the frame 7 project a distance beyond the side faces of the panels 8 and lie in the same plane with the outer surfaces of the letters 9. Each letter is formed with a retaining loop 10 which is embedded in the plastic material 8 before the same has set, so when a sign is ready for use, the letters will be held firmly in position.

The upper and lower sides of the frame are formed intermediate their ends with the inwardly projecting lugs or bosses 11, which are formed with threaded openings 12 to receive fastening members, whereby the sign may be conveniently secured to a support, not shown.

It will be noted that the concave formation of the inner face of the frame 5 secures the plastic layers firmly in position and that the wire mesh acts somewhat as a reinforcing element.

From the foregoing description taken in connection with the accompanying drawings, it will be apparent that I have provided a very simple, practical and durable sign, which may be cheaply manufactured, so as to sell at a relatively low price.

While I have shown and described the preferred embodiment of my invention, it will be understood that minor changes in construction, combination and arrangement of parts may be made without departing from the spirit and scope of the invention as claimed.

Having thus described my invention, I claim:

A sign of the class described including an elongated frame substantially concavo-convex in cross section and having the concave flanges disposed inwardly to provide a plastic receiving channel, a wire mesh secured to the inner concave face of the frame cen-

trally between the edges thereof, and panels
of plastic material applied to the opposite
sides of the mesh and seated in the groove
or channels of the frame, and a plurality
5 of letters embedded in the plastic panels,
and means on the inner ends of said letters
for anchoring the same within the panels.

In testimony whereof I affix my signature
in presence of two witnesses.

JOHN J. SPINKS.
